CLAIM

The ornamental design for an X-ray apparatus for dental whole jaw, as substantially shown.

DESCRIPTION

FIG. 1 shows a left-side elevational view of the X-ray apparatus for dental whole jaw showing our new design;

FIG. 2 shows a front elevational view thereof;

FIG. 3 shows a right-side elevational view thereof;

FIG. 4 shows a top plan view thereof;

FIG. 5 shows a bottom plan view thereof;

FIG. 6 shows a rear elevational view thereof;

FIG. 7 is a top front perspective view as seen from the top and front of FIG. 2; and

FIG. 8 is a bottom and rear perspective view as seen from the rear and bottom of FIG. 2.
